[57] **CLAIM**

The ornamental design for an orthodontic elastic application tool, as shown and described.

DESCRIPTION

FIG. 1 is a perspective view of an orthodontic elastic application tool showing my new design;

FIG. 2 is a front elevational view thereof;

FIG. 3 is a left end elevational view thereof;
FIG. 4 is a bottom plan view thereof, the top view being a mirror image;

FIG. 5 is a right end elevational view thereof;

FIG. 6 is a rear elevational view thereof.

The dotted lines represent a handle to illustrate environment, but are not a part of the design.
